(57) **CLAIM**

The ornamental design for a housing for a firearm sound suppressor, as shown and described.

DESCRIPTION

FIG. 1 is a front perspective view of a housing for a firearm sound suppressor showing the new design;

FIG. 2 is a rear perspective view thereof;

FIG. 3 is a front side elevational view thereof;

FIG. 4 is a rear side elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a cross-sectional view thereof taken between lines 9-9 of FIG. 5; and

FIG. 10 is a cross-sectional view thereof taken between lines 10-10 of FIG. 5; and,

FIG. 11 is a right side elevational view of the housing implemented as part of an example firearm sound suppressor mounted on an example firearm.

The broken lines in the drawings illustrate environmental features and form no part of the claimed design.
